UNITED STATES PATENT OFFICE.

JAMES THOMAS McNALLY, OF CHICAGO, ILLINOIS.

GRAIN-CAR.

No. 901,183.

Specification of Letters Patent.

Patented Oct. 13, 1908.

Application filed December 21, 1907. Serial No. 407,583.

To all whom it may concern:

Be it known that I, JAMES THOMAS McNALLY, a citizen of the United States, and a resident of Chicago, in the county of Cook and State of Illinois, have invented a new and Improved Grain-Car, of which the following is a full, clear, and exact description. This invention has reference to improvements in cars particularly adapted for use in hauling grain or for hauling such other freight as may be conveniently transported in an ordinary box-car.

The car is designed to discharge the grain through a portion of its floor which is provided with a double bottom having openings, with the openings of one bottom movable into and out of register with the openings of the other bottom. A door is adapted to cover these perforated bottoms when the car is to be used as an ordinary box-car, and is also adapted to cover one of the door openings in the side of the car when the car is to be used in hauling grain.

Reference is to be had to the accompanying drawings forming a part of this specification, in which similar characters of reference indicate corresponding parts in all the views.

Figure 1 is a cross-section through a car embodying my invention, substantially on the line 1—1 of Fig. 2, showing one of the inner doors moved to cover one of the door openings as when the car is used in hauling grain, and the other door turned down to cover the perforated bottoms as when the car is used as an ordinary box-car; Fig. 2 is a fragmentary sectional plan of the car, with the parts disposed in the position illustrated in Fig. 1; Fig. 3 is a cross-section through the car floor; Fig. 4 is a section on an enlarged scale, illustrating the latching means for locking one of the inner or grain doors over the perforated bottoms, and for locking a movable leaf to and in the plane of the door; Fig. 5 is a fragmentary sectional view through one of the side sills of the car, showing the mechanism for sliding one of the perforated bottoms with respect to the other; Fig. 6 is a fragmentary sectional view, showing the latch for latching the hinged leaf of the grain door to the stationary leaf; and Fig. 7 is a vertical section, showing the manner in which the grain doors are connected with the door jambs.

My invention is shown applied to a car,

embodying the characteristic features of an ordinary box-car, such, for example, as the outside doors 10 arranged at opposite sides and covering the side door openings. The floor of the car opposite these door openings is depressed between each side sill 11 and the central sill 12, and in each depression is located a double bottom composed of a fixed lower bottom 13, and an upper bottom 14, slidably supported on the lower bottom and in direct contact therewith. Each of these bottoms has a series of rows of openings 15, as best shown in Fig. 2, with the openings of one row arranged in the intervals of the openings in the next adjacent rows, which admits of a large open area being provided in each bottom without making the same unduly weak.

For moving the slideable bottom 14 with respect to the fixed bottom 13, in each depression, to carry the openings into and out of register, the former is attached to nuts 16 through intermediary connecting portions passing through slots 17, in the fixed bottom 13, as shown in Fig. 3. The nuts 16 are at each side of the car are threadedly connected with a screw 18, which is supported in a suitable bearing at its inner end on the cross-sill 12, as shown in Figs. 1 and 3, and at its outer end is forked or bifurcated for pivotally receiving a handle 19, by which the screw is actuated. This handle, as best shown in Fig. 5, is, when not in use, foldable in a recess in the outer face of the adjacent side sill, and has a slot at its free end provided with a transversely-arranged aperture for receiving and registering with the aperture in a keeper 20. When the handle is passed to this inoperative position it is adapted to be locked by a car seal 21, passing through the aforesaid apertures.

As shown in Fig. 1, at each side of the car, the center and the side sills are rabbeted on their opposed faces, providing shoulders, on which the fixed bottom 13 seats; this rabbeting being of such depth to also admit of the upper slideable bottom 14 passing thereinto, whereby it will be impossible for the grain to pass in between the center sill and the opposed edge of the slideable bottom 14, when the said bottom is in the position illustrated on the right-hand side of the car in Fig. 1. Each side sill 11 is further rabbeted on its inner face, providing a shoulder, on which is seated and secured a board 22, the same be-

ing spaced from the fixed bottom 13 sufficiently to closely fit the bottom 14 and prevent the passage of the grain between this last-named bottom and the side sill. On top of each side sill is the usual door-plate 23 which overhangs the upper rabbeted portion of the side sill, and in connection therewith forms a groove for receiving the lower edge of a grain door 24, this door being adapted to close the adjacent door opening in the side of the car, and also fill the depression over the fixed and movable perforated bottoms, and in which last-named position its upper face is flush with the car floor proper and gives to said floor an unbroken appearance. The door 24 has angularly-arranged apertured plates 25 secured to its outer face near the bottom, which slidably embrace upright guide-rods 26 let into grooves in the door jambs, as best shown in Fig. 2. This particular connection of the door with the door jambs permits of the door being moved from a horizontal position to an upright position and vice versa, without hanging or binding. The door 24 has an upper leaf 27 hinged thereto, and a fixed leaf 28 attached to the inner face of the lower and principal door section. This fixed leaf of the door has a spring-latch 29 in its upper edge, adapted to engage with the leaf 27, as shown in Fig. 6, and lock these two leaves together. With the parts of the door thus assembled, the door may be turned down into the adjacent depression of the floor, in which position the board 22 and leaves 27 and 28 will form a continuous covering over the double bottom, as clearly shown at the right-hand side of Fig. 1.

In connection with the lower and principal portion of the door is a latch in its upper edge comprising a spring-pressed bolt 30, adapted to lock the leaf 27 in a plane therewith when the door is extended at the side of the car, or to lock the door to the central sill of the car when the door occupies a depressed position. The bolt of this latch is forced to a retracted position when desired to unlock the leaf or door from the central sill, by a hand lever 31, the latter having an angular end engaging in an opening of the bolt, and is seated in a recess in the door when turned to an inoperative position. By lifting this handle when the door is located in one of the floor depressions, the same will be unlocked and can then be lifted to an upright position.

From the construction shown and described it will be apparent that I have produced a car which is especially adapted for hauling grain and such other like materials, or may be conveniently employed for transporting any kind of freight for which an ordinary box-car is adapted.

The invention as shown and described may obviously be modified in particulars

without departing from the nature thereof as defined in the claims annexed.

Having thus described my invention, I claim as new and desire to secure by Letters Patent:

1. A car having a floor provided with a depressed portion arranged above the under side of the floor sills, a double bottom in said depressed portion, each having openings, means for lineally sliding one of said bottoms to move the openings into and out of register with the openings in the other bottom, and a door for filling the depression in the car floor and covering said openings. 70

2. A car having a floor provided with a depressed portion arranged above the under side of the floor sills, a double bottom in said depressed portion, each bottom having openings, means for sliding one of said bottoms transversely of the car to move the openings into and out of register with the openings in the other bottom, said car having a door opening adjacent to the depression in the floor, and a door movable either to fill the depression in the car floor and cover said 90 bottom, or to cover the door opening. 85

3. A car having two perforated members in the floor thereof arranged above the floor sills and located one above the other and with one of said members lineally movable 95 with respect to the other to carry the perforations into and out of register, said car having a door-way located adjacent to said members, and a door adapted to form a portion of the floor and cover said members, or 100 cover the door opening.

4. A car having a door opening, a door adapted to form either a portion of the floor of the car or cover said door opening and having a movable leaf, and a latch adapted 105 either to lock the leaf in a plane with the door or lock the free edge of the door in the car floor.

5. A car having a door opening and provided with a depression in the floor thereof adjacent to said door opening, a door adapted to be either seated in said depression and form a part of the floor, or be moved to an upright position to cover the door opening, a hinged leaf forming an extension of the 110 car door, adapted to be folded upon the inner face thereof, and a lever fixed to the inside of the door forming a continuation of the hinged leaf when the door is seated in the car floor. 115

6. A car having a floor, a portion of which is provided with a double bottom, each of the bottoms having openings movable into and out of register with the openings of the other bottom, said openings being arranged 125 in rows, with the openings of one row located in the intervals of the adjacent rows.

7. A car having a floor, a portion of which is provided with a double bottom, each bottom having openings movable into and out 130

5 of register with the openings of the other bottom, a screw arranged transversely of the car having connection with one of said bottoms for sliding it relatively to the other, and an actuating handle pivotally connected to the screw at the side of the car.

8. A car having a floor, a portion of which is provided with a double bottom, each bottom having openings movable into and out 10 of register with the openings of the other bottom, a screw arranged transversely of the car having connection with one of the bottoms for sliding it relatively to the other, an actuating handle pivotally connected to the 15 screw at the side of the car movable into a groove in the adjacent side sill, and means for securing the handle in said groove.

9. A car having a floor, a portion of which is provided with a double bottom, the under 20 bottom being fixed relatively to the car, and each of said bottoms having openings, and means for linearly sliding the upper bottom for carrying the openings thereof into and out of register with the openings of the lower bottom.

25 10. A car having a floor, a portion of which is provided with a double bottom, the lower bottom being fixed, and the upper bottom being slidably mounted in direct contact with the lower bottom, each of said bottoms having openings movable into and out of register.

30 11. A car having a door opening and provided with a depressed portion in the floor thereof adjacent to said opening, a double bottom located in the depressed portion of the floor, each bottom having openings movable into and out of register with the other, vertically-arranged guide-rods at the opposite sides of the door opening, and a door 35 connected with said rods adapted to be seated in the depressed portion of the floor and

form a part thereof, or be moved over the door opening.

12. A car having a door opening and provided with a depressed portion in the floor thereof adjacent to said opening, a fixed bottom and a movable bottom located in the depressed portion of the floor, each of which has openings movable into and out of register with the openings of the other, a door having a fixed leaf secured to the inner face thereof, and a movable leaf hinged at its upper edge, and means for locking the hinged leaf directly to the fixed leaf, said door being 45 adapted when turned to an upright position to cover the car door opening, or, when the hinged leaf is locked to the fixed leaf, to be seated in the depression of the car floor and form a part thereof.

50 13. A car having a door opening and provided with a depression in the floor thereof adjacent to said opening, a door-plate within the door opening overhanging said depression, and a door for the door opening adapted to be seated in said depression, with the lower edge thereof located under said plate and forming a part of the car floor.

55 14. A car having a door opening and two flat bottoms in close contact in the floor thereof, each provided with openings, means for sliding the upper bottom to carry the openings thereof into and out of register with the openings in the lower bottom, and a door adapted to seat in the floor and cover 60 said bottom, or be moved to cover the door opening.

In testimony whereof I have signed my name to this specification in the presence of two subscribing witnesses.

JAMES THOMAS McNALLY.
